CLAIM

The ornamental design for a pendant, as shown and described.

DESCRIPTION

FIG. 1 is a bottom view;

FIG. 2 is a top view;

FIG. 3 is a front view, being identical to the rear view;

FIG. 4 is a left side view, being identical to the right side view;

FIG. 5 is a front, top perspective view; and,

FIG. 6 is a rear, bottom perspective view.

The broken lines shown are for purposes of illustrating contour only, and form no part of the claimed design.
